UNITED STATES PATENT OFFICE.

ANDREW CHRISTIAN ANDERSEN, OF DETROIT, MICHIGAN, ASSIGNOR TO TERNSTEDT MANUFACTURING COMPANY, OF DETROIT, MICHIGAN, A CORPORATION OF MICHIGAN.

WINDOW-REGULATOR OPERATOR AND CLUTCH.

Application filed July 19, 1924. Serial No. 726,948.

This invention relates to a sliding window regulator operator and clutch. It is the object of the present invention to provide an actuator and a lock for window regulators which comprises a single lever which when pushed in either direction will automatically release the clutch and permit the window to be raised or lowered. On the other hand, when the thrusting effort is released, the clutch will lock and hold the window in almost any desired intermediate position.

In the drawings:

Fig. 1 is an inside elevation of the top of 15 the window well.

Fig. 2 is a side elevation of the combined operator and clutch in its central or locking position.

Fig. 3 is a view of the clutch, similar to 20 Fig. 2, but showing the same when it is being actuated to raise or lower the window.

Fig. 4 is a section on the line 4—4 of Fig. 2.

Fig. 5 is a section taken on the line 5—5 25 of Fig. 2.

It is desirable with the rear quarter windows of an automobile closed body to use a regulator operating handle which is supported either on the horizontal bottom garnish moulding or the vertical side garnish moulding of the car. This removes the handle from a position below the seat where it is liable to catch on ladies' garments. It is the object of the present invention to provide 30 a combined sash operator and lock which will automatically release when thrust in either direction. A slide of this general nature is shown in the prior Heintz Patent, No. 1,430,647, but this requires the pinching together of two levers before the release is 35 effected.

Sliding sash holders are quite common and have been used in connection with rear quarter windows. Most of these sash holders, however, require a distinct unlocking movement, furthermore, they do not operate a window lift, but simply attach directly to the sliding sash. Transom openers are also in common use which combine a sliding 40 actuating device with a locking device, but most of these work on the principle of releasing by pinching two levers together.

The object of the present invention is to

provide a simple regulator which automatically unlocks when thrust is placed on the handle in either direction. This is the principle of operation now employed in most regulators which have a rotating crank handle, but so far as I am aware it has never been employed or worked out in the sliding window regulator handle.

a designates a flanged channel like track which is secured to the inside of the window well below the garnish moulding *b*. The bottom flange of this track is preferably 65 notched as at *c*. Fitted into this C-like cross section track is a sliding carriage *d* comprising a stamped metal member having a strap portion offset at the center to form the housing *e* while the ends of the 70 strap are riveted to the fiber strips *f* to make the slide noiseless and easily operated.

The housing has a pair of spring supporting lugs *g* struck out of the stock and around these is looped and anchored a wire spring *h* which in effect is a double wish bone or safety pin type of spring. The two ends of this double wish-bone spring engage the lug *i* which is stamped out of the rocking lever or lever *j*. This lever *j* is a sort of inverted T-shaped, with a pair of nubs *k* at either end of the bar of the T to act as rockers, while the depending portion *m* that passes through the slot *n* in the carriage stamping serves as a sort of keel or center-board (to use a homely comparison) to prevent the rocking lever from being tipped over or getting out of its proper position and assembly. The lever cannot have a permanent fulcrum in the way of a stationary pivot, 80 as it is alternately rocked on two separate fulcrums. It is desirable that it have something in the way of a keel member or centering device which will keep it from getting out of its proper place.

The depending portion *o* of the carriage stamping is connected by a pivot with the arm *q* which is part of the window regulating apparatus, more clearly shown and described in my co-pending application, No. 725,759. The lug *i* is arranged to be engaged or shot into anyone of the notches *c* of the track when the lever *j* is in its central position. It is obvious that it is only rocked from this central position when the handle portion *r* is grasped to slide the carriage in

either direction. When the handle is so grasped, the lever rocks on either one nub or the other as is plainly shown in the full line and dotted line in Fig. 3. This serves 5 to lift the lug out of the notch and release the carriage, and consequently unlock the sash.

The apparatus that I have here shown forms a positive lock for engaging the window. It will be obvious, however, that the notches could be omitted and the lug modified to form a frictional engagement with the track, which would probably take a much stronger spring, but which plainly comes 10 within the spirit of my invention and hence is incorporated with the breadth of the claims stated below.

What I claim is:

1. A sliding window operator and clutch, 20 having in combination a track and sliding hand lever guided along the track and arranged to lock on the track at any one of a plurality of points while in its central position, but released when rocked in either direction when one grasps the handle to slide the operator.

2. A sliding window operator and clutch having in combination a track, provided with notches, a carriage guided along the 30 notched track, and a handle by which the carriage is moved, arranged to normally engage one of said notches but automatically lifted out of the notches when the handle is moved.

3. A sliding window operator and clutch, 35 comprising a track, a slideable carriage guided on the track and a hand lever rockingly mounted on the carriage and normally locking at any one of a plurality of points on the track against sliding movement of the carriage, said lever however fulcrumed so as to release the lock when the lever is actuated to slide the carriage.

4. A sliding window operator and clutch, 45 having in combination a track, a sliding carriage guided on the track, and a double fulcrumed hand lever mounted on the carriage which normally locks with the track at any one of a plurality of points against movement of the carriage on the track when in 50 undisturbed position, but which rocks to re-

lease the clutching action when actuated to slide the carriage in either direction.

5. A sliding window operator and clutch, having in combination a track, a carriage 55 slidably guided on the track, a double fulcrumed hand lever supported on the carriage and normally centralized by a spring, and serving when in a central position to lock the carriage against sliding on the track, but 60 rocking when actuated in either direction to slide the carriage so as to release automatically the carriage from its locked relation with respect to the track.

6. A sliding window operator and clutch, 65 comprising a carriage, a track on which the carriage is guided, a lever having a pair of fulcrums and a depending centering device, and a spring tending to hold the lever in its central position to lock the carriage against 70 sliding movement on the track, whereby when the lever is grasped to slide the carriage in either direction, the same rocks on one fulcrum or the other to release the carriage from a locked relation with respect to 75 the track.

7. A sliding window operator and clutch comprising a notched track and a device including a hand lever slidably guided on the track, the said lever being ordinarily spring 80 pressed to have a portion engage with one of the notches of the track, it being rockable, automatically to release from the notch when the lever is operated to shift the device along the track.

8. A sliding window operator and clutch, 85 comprising a track having a C-like cross section, a carriage in the form of a stamping having portions engaged in the channels formed at the top and bottom of the C to 90 establish a sliding relation between the track and the carriage, and a lever fulcrumed on the carriage and arranged to engage with the track when in undisturbed position, and a spring for maintaining the lever in engagement with the track, said lever however fulcrumed on the carriage to release it from the track when actuated to slide the carriage 95 on the track.

In testimony whereof I have affixed my 100 signature.

ANDREW CHRISTIAN ANDERSEN.
